UNITED STATES PATENT OFFICE.

PAMPHILUS SCHMITZ, OF SAN FRANCISCO, CALIFORNIA.

CAR-SEAL.

1,217,077.

Specification of Letters Patent. Patented Feb. 20, 1917.

Application filed June 14, 1916. Serial No. 103,667.

To all whom it may concern:

Be it known that I, PAMPHILUS SCHMITZ, a citizen of the United States, and a resident of San Francisco, in the county of San Francisco and State of California, have invented an Improvement in Car-Seals, of which the following is a specification.

My invention relates to car seals, and it consists in the combinations, constructions, 10 and arrangements herein described and claimed.

An object of the invention is the provision of a seal of simple construction for attachment to freight cars and the like, whereby 15 the goods therein cannot be tampered with or a fraud committed without detection, and to this end the invention includes a main casing in which is inclosed and locked a part of an identification strip, the other part being detached, before the seal is locked, and 20 separately forwarded to the same destination as the goods.

Another object is to provide a novel means for locking the identification strip in 25 the main casing of the seal including, in addition to said main casing, an auxiliary casing or compartment in which is mounted a locking device for receiving the ends of a shackle member and retaining the same in locking 30 position. This shackle member engages, when in locking position, a closure member which incloses the identification strip and thereby prevents fraudulent removal or substitution of the same.

35 The inventive idea involved is capable of receiving a variety of mechanical expressions, one of which, for the purpose of illustrating the invention, is shown in the accompanying drawing, in which—

40 Figure 1 is a perspective view of the seal in locked position.

Fig. 2 is a longitudinal sectional view thereof.

Fig. 3 is an enlarged fragmentary section 45 illustrating the manner in which the shackle member is locked in position.

Fig. 4 is a section on the line 4—4 of Fig. 3.

Fig. 5 is a perspective view of a portion 50 of the shackle member.

Fig. 6 is a perspective view of the locking device for securing the shackle member in locking position.

Fig. 7 is a perspective view, partly broken 55 away, of the body portion of the seal.

Fig. 8 is a section on the line 8—8 of Fig. 7.

There is illustrated in the accompanying drawing, what is now believed to be a preferred form of the invention, in which, the body portion 10 of the seal is preferably formed from a single piece of material such as steel, brass or other strong metal. This metal is bent to provide the main casing 11 having sides 12 and an end 13. The other end 14 of the main casing 11 is formed by a continuation of the back of said casing which is bent to provide an auxiliary casing 15 for receiving the shackle locking device 16, which will presently be more specifically described. In forming the auxiliary casing 15 the material is bent so that the top of said auxiliary casing also provides the end 14 of the main casing 11. A sufficient length of material remains after forming the two sections 11 and 15 to provide a closure member 17 formed by extending the remaining portion of said material along the bottom of the casing 11 and then bending said material upon itself.

The closure member 17 which is preferably in the form of a flat plate is adapted to receive an identification strip 18 between it and the portion of the material resting upon the bottom of the casing 11. This identification strip is preferably made of a single length of water-proof paper or parchment one end of which is secured in the bottom of the casing by means of indissoluble cement, paste or the like and the material of the bottom and also the portion resting thereon is stamped out to provide eyelets 19 the flanges of which are bent over the strip, as best shown in Fig. 8. Intermediate the ends of the strip 18 the same is provided with a transverse perforated or weakened line 36 upon which is written any name with water-proof ink in such manner that portions thereof extend both above and below said line. The portion of the strip 18 between the line 36 and the free end thereof also has the same name written thereon, with waterproof ink and said portion of the strip is detached before the same is locked and sent to the same destination as the goods. When said goods are received, proper identification may be made by matching the ends of the strip where the same has been perforated, and it will be apparent that, by reason of the eyelet fastenings 19 and the use of in-

dissoluble cement, or the like, the portion of the strip remaining in the casing cannot be removed and replaced without detection. This fact affords absolute proof of any 5 tampering with the contents of the car, for if said portion or strip could be removed without damage thereto, the same could be used in a new casing. If desired, the number of the car may also be stamped on the 10 back of the casing.

The closure plate or member 17 is preferably locked in position so that access cannot be had to the strip 18 therebeneath, and to this end there is provided a shackle member 20 preferably of U-shaped formation and having its ends provided with flat transverse heads 21 of substantially spear shape having locking shoulders 22. The ends of the shackle member are inserted 20 through openings 23 formed in the end 13 of the casing 11, and extend exteriorly of the closure member 17, so that the same cannot be pulled outwardly. The ends of the sides 12 of the casing 11 adjacent the end 25 14 thereof are provided with flanges 24 which are turned inwardly and abut said end 14. The end 14 and flanges 24 are provided with registering openings 25 and 26 respectively in alinement with the openings 30 23 in the end 13, and adapted to receive the heads 21 of the shackle member 20.

The auxiliary casing 15 receives therein the locking device 16 which is preferably of a box-like formation and which has its top 35 27 provided adjacent each end thereof with indentations 28 having openings 29 therein which are in vertical alinement with the openings 23, 25 and 26. After the locking device 16 is placed in position in the auxiliary casing 15 the end flanges 30 are inserted between the top 27 of said locking device and the flanges 24, said flanges 30 being also provided with indentations 32 and openings 33, the latter registering with 40 the openings 29 formed in the top 27 and indentations 28 of the locking device. A pair of shackle engaging members 34 in the form of steel wires are arranged along the top 27 of the locking device and their ends 45 are inserted through openings 35 formed in said top whereby the end portions of said members 34 will extend beneath said top, a portion thereof being exposed through the openings 29. It will thus be seen that by 50 forcing the shackle member 20 inwardly the heads 21 will eventually contact with the exposed portions of the members 34 and spread the same apart until said heads have passed beyond said wires whereupon the latter will 55 spring back into normal position and engage the shoulders 22 of said heads and effectually prevent the shackle from being withdrawn.

What is claimed is:

65 1. A seal comprising a body portion

formed from a single piece of material bent to provide a main casing, an auxiliary casing and a closure in said main casing, an identification strip having one end secured in said main casing and inclosed therein by 70 said closure, a locking device mounted in said auxiliary casing, and a shackle member extending through said main casing and locked in position by said locking device for retaining said closure in closing position. 75

2. A seal comprising a body portion formed from a single piece of material bent to provide a main casing, an auxiliary casing and a closure in said main casing, an identification strip having one end secured in said main casing and inclosed therein by 80 said closure, a locking device mounted in said auxiliary casing, and means automatically locked in position by the insertion thereof into the locking device for retaining 85 said closure in closing position.

3. A seal comprising a main casing, an identification strip secured therein, a closure for said strip forming a portion of said casing, a locking device associated with said main casing, and a shackle member engaging 90 said closure and locked by said locking device to retain said closure in closing position.

4. A seal comprising a main casing, an identification strip secured therein, a closure for said strip, a locking device associated with said main casing, a shackle member extending through said casing and locked by said locking device to retain said 95 closure in closing position, and an auxiliary casing at one end of said main casing for inclosing said locking device. 100

5. A seal comprising a casing, an identification strip having one end secured therein, a closure for said strip forming a portion of said casing, and means extending 105 into one end of said casing and projecting through the other end thereof and engaging said closure for retaining the same in closing 110 position.

6. A seal comprising a casing, an identification strip having one end secured therein, a closure for said strip forming a portion of said casing, means extending 115 through said casing and engaging said closure for retaining the same in closing position, a locking device associated with said casing and engaging said means for locking the same in retaining position, and an auxiliary casing forming a portion of said main casing for inclosing said locking device. 120

7. A seal comprising a main casing, an identification strip of waterproof material therein, a closure for said strip, a locking device associated with said casing and having openings therein, and including resilient locking members having portions thereof arranged contiguous to said openings, and a shackle member extending through said 125 130

main casing and engaging said closure for retaining the same in closing position, said shackle member also projecting into the openings in said locking device and engaging said locking members whereby the hasp is locked in retaining position.

8. A seal comprising a main casing, an identification strip therein, a closure for said strip, a locking device associated with 10 said casing and having openings therein, and including resilient locking members having portions thereof arranged contiguous to said openings, and a shackle member extending through said main casing and engaging 15 said closure for retaining the same in closing position, the ends of said shackle member having heads to provide locking shoulders for engaging the locking members of 20 said device whereby said shackle is locked in retaining position.

9. A seal comprising a single sheet of material bent to form a main casing and an auxiliary casing, an identification strip secured in said main casing, a closure for said 25 identification strip also forming a part of the material of which said casing is made, a shackle member extending through said main casing and engaging said closure for retaining the same in closing position, said 30 shackle member also projecting into said

auxiliary casing, and means in said auxiliary casing for locking said shackle member in position.

10. A seal comprising a single sheet of material bent to form a main casing, and an 35 auxiliary casing, an identification strip secured in said main casing, a closure for said identification strip also forming a part of the material of which said casing is made, a shackle member extending through said 40 main casing and engaging said closure for retaining the same in closing position, and means in said auxiliary casing and automatically actuated by the insertion of said shackle member into said auxiliary casing 45 for locking said shackle member in position.

11. A seal comprising a single sheet of material bent to form a main casing and an auxiliary casing, an identification strip in 50 said main casing, a closure for said strip, a locking device in said auxiliary casing and a shackle member extending through said main casing and locked by said locking device in said auxiliary casing, to retain said 55 closure in closing position.
